UNITED STATES PATENT OFFICE.

LADIMIR H. SVOBODA, OF CLEVELAND, OHIO.

FAN.

1,357,261.

Specification of Letters Patent.

Patented Nov. 2, 1920.

Application filed October 2, 1918. Serial No. 256,569.

To all whom it may concern:

Be it known that I, LADIMIR H. SVOBODA, a citizen of the United States, residing at Cleveland, in the county of Cuyahoga and 5 State of Ohio, have invented certain new and useful Improvements in Fans, of which the following is a specification.

This invention relates to certain new and useful improvements in fans.

10 The primary object of the invention is to provide a portable fan including a casing which provides both a handle for manipulating the fan and a housing for containing the operating means for driving the fan 15 blade at one end of the casing.

Another object of the invention is to construct the casing or handle in sections so that the battery and motor forming the driving means for the fan blades and positioned 20 within the casing will be readily accessible for inspection.

A still further object of the invention resides in the novel formation of the fan blades and in the manner of removably 25 mounting the same upon the motor shaft.

A still further object of the invention is to provide supporting members upon the casing which are adapted to receive and hold the fan blades when the latter are removed 30 from the motor shaft.

A still further object of the invention resides in the specific construction, combination and arrangement of parts whereby the device is rendered practical and efficient for 35 the purpose for which it is designed and is capable of being disassembled to permit inspection or replacing of parts.

Other objects of the invention will be more readily understood from the following description and drawings wherein I have illustrated the invention in its preferred embodiment and in which drawings:—

Figure 1 is a longitudinal sectional view taken through a fan constructed in accordance with my invention.

45 Fig. 2 is a view looking at the fan blades from the rear thereof.

Fig. 3 is a detail showing the blade receiving end of the motor shaft.

50 Fig. 4 is a detail view showing the manner of removably securing the fan blades upon the motor shaft.

Fig. 5 is a view in side elevation of the casing showing the arrangement of the supporting clips for holding the fan blade, when 55 not in use.

Fig. 6 is a view taken on the line 6—6 of Fig. 5, and

Fig. 7 is a view similar to Fig. 6 taken on the line 7—7 of Fig. 5. 60

Fig. 8 is a detail view of the connection between the fan blades.

The casing or handle portion of my improved fan is made up of two main sections indicated respectively by the numerals 1 and 2. The rear end of the section 2 is open and is received in the open forward end of the section 1 being secured therein by means of the screws 3 passing through both of said sections as indicated. The rear end of the 70 section 1 is also open and is exteriorly threaded as indicated at 4 to receive a threaded closure cap 5. The forward end of the section 2 is also closed and is equipped with an integral hood 6 which is adapted to partly 75 inclose the fan blades as will be later set forth.

Within the casing 1 is positioned a battery 7, having its forward end abutting stop lugs 8 integral with the inner wall of the 80 casing and its rear end engaged by a spring 9 carried by the cap 5 and serving to retain the forward end of the battery engaged with said stop lug. This battery is electrically connected as shown with a motor 10 carried 85 within the section 2. This motor and battery may be of any conventional form suitable for the purpose and in the circuit connecting the same is included a suitable electrical switch comprising the spaced contacts 90 11 and 12 secured upon the casing as indicated in Fig. 1.

The motor shaft indicated at 13, is extended through the forward wall of the section 2 and upon the extended end of this 95 shaft is mounted the fan blades 14 and 15.

The blade receiving end of this shaft as shown in Fig. 3 is reduced and squared as indicated at 16 and is provided with opposite side grooves 17. The fan blades preferably 100 two in number are extended at right angles to one another in operative position and are provided intermediate their ends with registering openings to receive the squared end of the shaft as in Fig. 2. To assist in maintaining these blades in proper angular position with respect to one another I provide a collapsible connection consisting of the links 18 and 19. The links 18 are pivoted at one end to the rear face of the blade 15 110 upon opposite sides of the center of the blade and extend in opposite direction to one an-

other for engagement with the correspondingly positioned links 19 carried by the blade 14. The free end of these links 18 and 19 overlap and are secured by pivot pins 20. 5 As more clearly shown in Fig. 8, each of the links 19 is provided upon opposite sides of the pivot pin 20 with conical projections 21 which are engageable with correspondingly shaped sockets or recesses 22 formed in the links 18. These conical projections when received in the sockets provided therefor maintain the links in extended position and thus aid in maintaining the blades at right angles to one another. As shown in Fig. 2, 10 these links may be readily moved from extended position to permit the fan blades to lie in engagement throughout their entire length.

One of the blades preferably the blade 20 14 in the present instance is equipped with a hook 23 having one end thereof pivotally secured to the forward face of the blade as indicated at 24 and having the opposite hooked end thereof provided with a lateral 25 extension 25 forming a finger piece. When the fan blades are arranged in proper angular position by means of the links 18 and 19 and slipped upon the reduced squared end of the shaft 13, this hook is then engaged with the groove 17 to prevent accidental removal of the blade. When it is desired to remove the blades, however, it is merely necessary to grasp the finger piece 25 and to swing the hook out of engagement 30 with the groove 17. The blades may then be readily removed and by forcing the links 18 and 19 from extended position as indicated by dotted lines in Fig. 2 the blades may be caused to lie flat upon one another 35 throughout their length, thus occupying a minimum amount of space.

To receive the blades when folded and not in use, I have provided a pair of clip members 25 and 26 secured to one side of the casing 40 adjacent opposite ends thereof as indicated in Fig. 5. These clip members as more clearly indicated in Fig. 6 are preferably U-shaped in configuration, with the inner rims thereof riveted to the casing as 45 indicated at 27.

From the foregoing it will be seen that I have provided a practical and convenient form of portable fan and it will be understood in this connection that the hood 6 50 may be omitted if desired so that the handle casing may be readily received in the pocket of the user when the fan blades are detached from the motor shaft and engaged with the holding clips provided therefor.

60 In practice, after the motor and battery have been positioned in the sections 2 and 1 respectively, these sections are connected together by the screws 3. The cap 5 is then

threaded upon the rear end of the section 1 and the spring 9 carried by this cap will 65 retain the battery 7 properly engaged with the stop lug 8 to prevent shifting of the battery within the casing. The fan blades are then arranged as shown in Fig. 2 and are slipped upon the blade receiving end of the 70 shaft 13, being held thereon by means of the hook 23 engaging the groove 17. After using the fan, the blades may be readily removed from the shaft by disengaging the hook 23 from the groove 17. The blades 75 are then collapsed as indicated by dotted line in Fig. 2 and are inserted in the holding clips 25 and 26.

The foregoing description and accompanying drawings have reference to what 80 might be considered to be the preferred or approved form of my invention. I desire it to be understood that I may make such changes in the construction, combination and arrangement of parts, materials, dimensions et cetera as may prove expedient and fall within the scope of the appended claims.

Having thus fully described my invention what I claim as new and desire to secure by Letters Patent, is:—

90 1. In a portable fan, the combination with a rotatable shaft having an end thereof reduced and provided with oppositely arranged grooves, of a plurality of fan blades slidably received on the reduced end 95 of said shaft, and a hook member carried by one of said blades and engageable with said grooves to retain the said blades in position.

100 2. In a fan, the combination with a rotatable shaft having a reduced squared end, of a pair of fan blades centered on the squared end of the shaft and crossing each other to provide vertical and horizontal blades, a collapsible link pivoted at its ends 105 to the inner faces of the cross blades and connecting said blades on diametrical opposite sides of the said shaft, whereby said blades may be aligned to present only a single blade surface.

110 3. A portable fan, including in combination a rotatable shaft, separate fan blades removably mounted upon said shaft and extending at right angles to each other, collapsible links extending from each blade, on 115 one side thereof and pivotally connected with the adjacent blade, and means for retaining the links rigid so that the linked blades may be retained in the proper relative position during the operation thereof.

120 In testimony whereof I affix my signature in presence of two witnesses.

LADIMIR H. SVOBODA.
